UNITED STATES PATENT OFFICE

EDWIN JOWETT, OF KANSAS CITY, MISSOURI, ASSIGNOR TO THE BABCOCK & WILCOX COMPANY, OF BAYONNE, NEW JERSEY, A CORPORATION OF NEW JERSEY

FLUID HEATER

Application filed December 27, 1923. Serial No. 682,917.

My present invention relates to improvements in fluid heaters, and particularly in heaters of this sort in which the fluid circulates through tubes while being heated, and in which the tubes are connected at their ends by headers or the like.

My invention will be best understood from the following description and annexed drawings, in which Fig. 1 is a vertical section of a steam boiler economizer embodying my invention which I have adopted for illustrative purposes; Fig. 2 is a section on the line 2—2 of Fig. 1; Fig. 3 is a perspective of the headers and some of the tubes shown in Figs. 1 and 2, with the handhole covers removed; Fig. 4 is a plan, Fig. 5 an end elevation and Fig. 6 a section on the line 6—6 of Fig. 5, of the header shown in Fig. 3; Fig. 7 is a diagrammatic section showing the relation between the handhole covers in the illustrative form of the header, the upper handhole cover being a section on the line 7^a—7^a of Fig. 11, and the lower handhole cover being a section on the line 7^b—7^b of Fig. 9; Fig. 8 is a front view of one of the handhole covers shown in Fig. 7; Figs. 9 and 10 are respectively plan and elevation on a larger scale of the elliptical handhole closure, and Figs. 11 and 12 are respectively plan and elevation of the circular handhole closure.

Like reference characters indicate like parts in the several views.

In the illustrative form of my invention, the tubes 10 pass back and forth across a flue, as is well understood in economizer practice, the water for the economizer entering through a header 11 and passing out through a header 12. The pairs of pipes are connected at their ends by means of headers 13 which, in the form illustrated, are shaped so that each one connects the ends of two tubes only. By inclining these headers, as shown best in Fig. 2, the tubes in successive rows will be staggered.

Turning now to the illustrations of the specific header shown in Figs. 1 and 2, and particularly to the enlarged views thereof in Figs. 4, 5 and 6, the header has a front wall 14 having tube holes 15 and 16 therein and a rear wall formed in two planes, one portion

17 being parallel with the front wall 14 and the other portion 18 forming an angle with the front wall and with the portion 17. The rear wall is provided with a handhole opening opposite each of the tube openings 15 and 16, and the header is completed by the side walls 19 which are concentric at the ends with the tube holes 15, 16 and have straight portions connecting these concentric portions.

As best illustrated in Fig. 7, the handhole 20 in the portion 17 and opposite the tube hole 15 is circular, whereas the handhole 21 in the inclined portion of the rear wall 18 and opposite the tube hole 16 is elliptical. It will be noted that the ellipse has its minor axis 60 slightly larger than the diameter of the tube hole 16, and the opening is so located in reference to its tube hole 16 that one end of the opening 21 is substantially opposite the portion of the tube hole 16 farthest away from the other tube hole 15, while the other end of the major axis of the ellipse extends considerably beyond the periphery of the tube hole 16.

The header is preferably provided with internal handhole closures, so that they will be able to resist high pressures. The closure for the circular opening 20 is illustrated in Figs. 11 and 12, the cover 22 being circular in outline and provided with a seat 22' to fit against the inner face of the wall surrounding the opening 21. The cover 22 is provided with a slotted recess 23 in which engages the head 24 of a bolt 25 passing through a spider 26, the legs of which contact with the walls surrounding the opening 21 in the usual manner to draw the cover 22 into position against the inner walls of the opening 20. The cover 27 for the elliptical opening 21 is similar in construction to the circular cover 22, the cover 27 being provided with a seat 28 arranged to fit against the inner face of the wall surrounding the opening 21, and the cover 27 being provided with a recess 29 in which the head 24 of the bolt 25 engages, the bolt 25 in this case passing through a spider 30 similar in construction to the spider 26 but with its legs adapted to the elliptical opening. By the arrangement just described, I provide a header in which the internal covers for the handholes may be pro-

90
95
100

vided without unduly weakening the header and without disturbing the usual center distances of the tubes 10 in such constructions. While a circular cover, such as 22, is effective in closing a handhole internally, it will be obvious that it cannot be passed through the hole which it is to cover, and when such circular covers are used, they must be inserted through holes in other parts of the header. 10 On the other hand, elliptical covers, such as 27, may be passed through the holes which they are to cover, but, of course, such handholes are much larger than are necessary for expanding the tubes and the like in the holes. 15 15, 16. Consequently, if a header is made in the usual manner, with the rear wall parallel to the front wall, then an elliptical handhole removes so much of the metal between the two adjacent handholes that the header is 20 unduly weakened. By providing the angular face 18, I have added sufficient metal between the handholes 20 and 21 so that one of those handholes, as 21, may be elliptical and still leave considerable metal between the 25 two handholes. At the same time, both handhole covers may be inserted and removed through the elliptical opening 21, the circular cover 22 being dropped down and removed from the header through the opening 21, the 30 elliptical cover 27, of course, being passed through the same hole. This operation is facilitated by the fact that the interior angle between the portions 17 and 18 is less than 180°, as a workman inserting his hand 35 through the opening 21 may readily adjust the cover 22 in place. In other words, by my arrangement, I have provided a header which may have internal covers, and therefore be used in high-pressure work, and which 40 at the same time, does not unduly weaken the headers nor require a special spacing of the tubes. Any other suitable form of seat, instead of the flat seat with a gasket shown in the drawings, may be used on the fittings. 45 While I have shown my invention applied to an economizer, it will be understood that it may be applied to any fluid heater. When a single header is used as illustrated, to connect a pair of tubes only, the fluid will circulate in definite paths vertically, since there 50 is no communication laterally between the several headers 13. The inlet and outlet headers 11 and 12, however, must be continuous so as to supply the fluid to each of the 55 lowermost tubes 10 and permit it to pass out of the uppermost tubes 10. If desired, however, the headers 13 may be formed as a single header extending entirely across the fluid heater, in which case, the surfaces 17 and 18, 60 instead of being substantially circular, would be long and comparatively narrow, but would have the same angular relation to each other, as is shown in Fig. 6, for instance. It will also be obvious that if it is not desired to stagger the tubes, then the headers 13 would stand

vertical instead of in inclined relation, as shown in Fig. 2.

I claim:

1. In a fluid heater, circulating tubes and headers connecting the ends of the tubes, each of said headers having its front wall substantially at right-angles to the axis of the tubes and holes therein to receive the tubes, handholes in the rear wall of the header, each opposite a tube hole, the rear wall having the portion surrounding one of the handholes parallel to the front wall and the portion surrounding another handhole at an angle thereto, the handhole in the parallel portion being circular and the handhole in the non-parallel portion being elliptical, with the major axis of the ellipse parallel to the plane of the axes of the tubes and with one end of the major axis of the ellipse substantially opposite the side of the tube farthest from the other tube, and a closure for each handhole adapted to engage the inside of the rear wall of the header. 70 75 80 85

2. In a fluid heater, a bank of circulating tubes and headers each connecting the ends of a single pair only of said tubes, each header having a front wall, with tube holes into which the tube ends are entered, and a rear wall having two portions in planes at an angle to each other with a hand hole in each part opposite one of said tube holes, one of said handholes being circular and concentric with one of said tube holes and the other handhole being elliptical and eccentric to the other tube hole, and a closure for each handhole adapted to engage the inside of the rear wall of the header. 90 95 100

3. In a fluid heater, a bank of circulating tubes and headers each connecting the ends of a single pair only of said tubes, each header having a front wall, with tube holes into which the tube ends are entered, and a rear wall having two portions in planes at an angle to each other with a hand hole in each part opposite one of said tube holes, one of said handholes being circular and concentric with one of said tube holes and the other handhole being elliptical and eccentric to the other tube hole with the end of the major axis of the ellipse substantially opposite the side of its tube hole farthest from the other tube hole, and a closure for each handhole adapted to engage the inside of the rear wall of the header. 105 110 115

4. In a fluid heater, a bank of circulating tubes and headers connecting the ends of said tubes, the tubes being divided into pairs, with the ends of each pair entering tube holes in the front wall of a header and the rear wall of the header having two portions forming an angle with each other, each portion having a handhole therein, one of said handholes being circular and concentric with one of the tubes of one of said pairs and another of said handholes being elliptical and eccentric 120 125 130

to the other of the pair of tubes, and a closure for each handhole adapted to engage the inside of the rear wall of the header.

5. In a fluid heater, a bank of circulating tubes and headers connecting the ends of said tubes, the tubes being divided into pairs, with the ends of each pair entering tube holes in the front wall of a header and the rear wall of the header having two portions forming 10 an angle with each other, each portion having a handhole therein, one of said handholes being circular and concentric with one of the tubes of one of said pairs and another of said handholes being elliptical and eccentric to the other of the pair of tubes with the 15 end of the major axis of the ellipse substantially opposite the side of its tube farthest from the other tube of the pair, and a closure for each handhole adapted to engage the inside 20 of the rear wall of the header.

6. In a fluid heater, a bank of circulating tubes and headers connecting the ends of said tubes, the tubes being divided into pairs, with the ends of each pair entering tube holes in 25 the front wall of a header and the rear wall of the header having two portions forming an angle with each other, each portion having a handhole therein, one of said handholes being concentric with one of the tubes 30 of one of said pairs and another of said handholes being elliptical and eccentric to the other of the pair of tubes, and a closure for each handhole adapted to engage the inside of the rear wall of the header.

35 7. In a fluid heater, a header having front and rear walls, the front wall lying substantially in a single plane and having a pair of holes for the reception of tube ends and the rear wall being formed of two portions disposed opposite the tube holes and forming 40 an interior angle between them of less than 180°, one of said portions having a substantially round handhole and the other portion having a substantially elliptical handhole 45 therein, and round and elliptical covers respectively adapted to close said round and elliptical handholes by engagement with the inside of the rear wall.

EDWIN JOWETT.
